UNITED STATES PATENT OFFICE.

LOUIS E. SHAW, OF EAST ORANGE, NEW JERSEY.

ELECTRIC CLOCK.

1,400,832.

Specification of Letters Patent. Patented Dec. 20, 1921.

Application filed December 8, 1919. Serial No. 343,194.

To all whom it may concern:

Be it known that I, LOUIS E. SHAW, a citizen of the United States, residing at 179 North Parkway, East Orange, in the county 5 of Essex, State of New Jersey, have invented certain new and useful Improvements in Electric Clocks; and I do hereby declare the following to be a full, clear, and exact description of the invention, such as will 10 enable others skilled in the art to which it appertains to make and use the same.

The present invention relates to electric clocks, and particularly to those having an electromagnetically-operative actuating 15 mechanism for the movement thereof, including a spring which is wound intermittently for subsequently actuating the movement.

In prior clocks of this kind, the movement is not magnetically screened from the electromagnet, so that the magnetism thereof is liable to affect the accurate working 20 of the clock. In accordance with one part of my invention, the electromagnet has a 25 continuous core, preferably of annular form surrounding the movement and being of trough section with the flanges directed outwardly of the base and inclosing the energizing winding. Thus substantially all the 30 lines of force external of the core extend outwardly of the movement between the poles formed by the flanges of the core. Besides magnetically screening the movement in this way, this form of magnet has continuous poles nicely providing for the 35 actuation of a number of armatures at convenient places around its periphery, and mechanically protects the energizing winding.

40 Irrespective of the form of the core of the electromagnet, my invention comprehends, as another of its parts, two armatures which are connected to springs and which are oppositely pivoted, that is which extend in 45 opposite directions from their pivots. This arrangement tends to eliminate the disturbing effects of shock and vibration to which the clock is subjected when mounted on a moving vehicle, such as an automobile. The 50 result may be enhanced by having the armatures diametrically disposed to each other, and by extending the springs in op-

posite directions from their fixed connections and connecting them at diametrically opposite points to a pawl-carrying member 55 which is journaled on the arbor of the movement. By substantially balancing the pawl-carrying member on both sides of the arbor, the effect of shock or vibration to the clock is further neutralized on the ratchet with 60 which the pawls engage for actuating the movement.

The invention further comprehends, as another of its parts, co-operative electric contacts arranged in the circuit between the 65 energizing winding of the electromagnet and the source of current, the movable one of the contacts being mounted on a pivoted arm which carries an armature of the electromagnet and which extends into the path 70 of the movement of a movable part of the electromagnetically-operative actuating mechanism of the clock. Thus as soon as the contacts close, the electromagnet first draws them firmly into engagement to more 75 reliably furnish current to the winding, and thereafter they are quickly and forcibly separated by a blow from the actuating mechanism as, for instance, when the springs become fully stressed thereby. 80

In electric clocks of this kind, the pressure of the electromagnetically-operative actuating mechanism on the escapement of the movement is removed when the spring is being rewound, so that, notwithstanding 85 the briefness of each rewinding period, the escapement becomes subject in those periods to unsteady movements affecting the accuracy of the clock. In accordance with this part of my invention, the pressure of the 90 actuating mechanism on the escapement is replaced, while the spring is being rewound, by an interwinding mechanism comprising, if desired, a member adapted to engage the escapement to exert pressure on it, and 95 means for forcing the member into engaging position while the spring is being rewound. Preferably, this member is a yieldable arm to preclude shock to the escapement, and is carried by an armature of the 100 electromagnet that serves to rewind the spring. Thus whenever the electromagnet is energized to rewind the spring, the interwinding mechanism is engaged with the es-

capement to replace thereon the pressure of the actuating mechanism.

In the accompanying drawings illustrating the preferred embodiment of the invention, in application, as an example, to an automobile clock which is devoid of the usual operating spring but is provided with comparatively light springs adapted to be retensioned at brief intervals.

- 10 Figure 1 is a rear view, partly broken away and partly diagrammatic, particularly showing the electromagnetically-operative actuating mechanism; Fig. 2 is a diagrammatic view of that mechanism at the beginning of the rewinding movement; Fig. 3 is a similar diagrammatic view at the end of the rewinding movement; and Figs. 4, 5 and 6 are sections on lines 4-4, 5-5 and 6-6, respectively, of Fig. 1.
- 15 20 The clock is of circular outline having a case 1 of non-magnetic material adapted to be fastened by screws to the dash board of an automobile. The movement includes an escapement 2, a reset mechanism 3, and an 25 arbor 4 on which is fast a ratchet 5.

Surrounding the movement is an electromagnet having an iron core of trough section comprising a base 6 and the two flanges 7 directed outwardly of the movement and 30 forming continuous poles around its outer circumference, so that substantially all the magnetic lines of force external of the core extend between the poles in a direction away from the movement to screen it magnetically. The member 8 is journaled on the arbor 4, and carries diametrically-disposed pawls 9 spring pressed into engagement with the ratchet 5. This member is attached at diametrically opposite points to the 35 springs 10 which extend in opposite directions from fixed connections at 11. By means of the rods 12, this member is connected at diametrically opposite points with the armatures 13 pivoted to the core at diametrically opposite points and extending in 40 opposite directions, up and down, from their pivots. The member 8 is substantially balanced with respect to the arbor 4, so as to remain in stability in whatever position it 45 may have.

As a result of the balanced arrangement noted, a blow or vibration imparted to any part of the case 1 is transmitted equally to opposite points of the ratchet 5 through the 55 diametrically disposed pawls 9, thus neutralizing the effect on the escapement 2 of the movement and precluding interference with the accurate operation thereof.

The electromagnet has an energizing 60 winding 14 wound around the base 6 between the flanges 7 of the core. One terminal of this winding is connected to a battery 15, and the other terminal is connected through the spring arm 16 forming the 65 movable electric contact in co-operation

with the stationary electric contact 17. This spring arm 16 also carries the armature 18 normally held by the arm in a position away from the flanges 7 of the electromagnet core. The spring arm 16 is also fast with the outer end of the arm 19 of the bell crank lever pivoted at 20 and having its other arm 21 extending downwardly between prongs 22 and 23 of member 8, so as to lie in the path of movement of those prongs.

70 The electromagnet core is also provided with an armature 24 pivoted at 25 and carrying a flat spring arm 26 resting on the teeth of the ratchet 5 but adapted to be forced into engagement therewith when attracted by the core. This interwinding mechanism functions while the springs 10 are being retensioned, to replace at that time the pressure of those springs exerted through the pawls 9 on the ratchet and thereby eliminate the unsteady action of the escapement that would result if pressure on it were not maintained.

75 Starting with the springs fully extended as shown in Fig. 3, the operation of the clock is as follows: As the springs contract in turning the member 8 anticlockwise, the pawls 9 maintain pressure on the ratchet 5 to drive the escapement 2 and advance the hands of the clock, the electric contact 16 moving toward contact 17 through the medium of the bell crank lever 19, 21 until engaged therewith, as shown in Fig. 2. Thereupon, the circuit between the battery 15 and the winding 14 is closed and the 80 electromagnet energized. The armatures 13 are quickly and forcibly attracted into engagement with the flanges 7 of the core, turning the member 8 in a clockwise direction and extending the springs 10 as the 85 pawls 9 slip backward over one or more teeth of the ratchet. At the same time, the armature 18 is attracted to the flanges 7 and thereafter holds the movable contact 16 in firm engagement with the contact 17, until at such time that the prong 22 strikes the arm 21 a blow to positively disengage the contacts and interrupt the circuit to the 90 winding 14.

95 As soon as the electromagnet is energized, and while the armatures 13 start moving toward the flanges 7 of the core, the armature 24 is also attracted toward the flanges 7 of the core. In doing so it forces the spring arm 26 into engagement with a tooth of the ratchet 5, to thereby replace the normal driving pressure of the pawls 9 on the ratchet with the pressure exerted by the core of the electromagnet on the armature 24 through the yieldable arm 26.

100 105 110 115 120 125 125 As soon as the electric contacts 16, 17 are disengaged, the magnetic attraction between the flanges 7 of the core and the armatures 18 and 24 ceases. This cycle is repeated at brief intervals, every minute or so, de-

pending upon the movement of contact 16 between open and closed positions with respect to the coöperative contact 17.

Having thus described my invention, what

5 I claim is:

1. In an electric clock, a movement, and electromagnetically - operative actuating mechanism therefore including an electromagnet having a continuous core of trough 10 form magnetically screening the movement.

2. In an electric clock, a movement, and electromagnetically-operative actuating mechanism therefor including an electromagnet having a continuous core surrounding 15 the movement.

3. In an electric clock, a movement and electromagnetically-operative actuating mechanism therefor including an electromagnet having an annular core surrounding 20 the movement.

4. In an electric clock, a movement, and electromagnetically-operative actuating mechanism therefor including an electromagnet having an annular core of trough 25 form surrounding the movement.

5. In an electric clock, a movement, and electromagnetically - operative actuating mechanism therefor including an electromagnet having a continuous core of trough 30 form with its poles directed outwardly of the movement.

6. In an electric clock, a movement and electromagnetically - operative actuating mechanism therefor including an electromagnet 35 having a continuous core of trough form which surrounds the movement and which has its poles directed outwardly of the movement.

7. In an electric clock, a movement, and electromagnetically - operative actuating mechanism therefor including an electromagnet having an annular core which surrounds the movement and which is of trough 45 form with its flanges directed outwardly out of its base.

8. In an electric clock, a movement, and electromagnetically - operative actuating mechanism therefor including an electromagnet having a continuous core of trough 50 form surrounding the movement and containing an energizing winding.

9. In an electric clock, a movement, and electromagnetically - operative actuating mechanism therefor including springs and 55 two oppositely-pivoted armatures connected to said springs and adapted to stress them when attracted by the core of the electromagnet for subsequently actuating the movement.

60 10. In an electric clock, a movement, an electromagnet having a core and diametrically - disposed oppositely-pivoted armatures, and springs connected to the armatures and to the movement, said armatures being

adapted to stress the springs when attracted by the core of the electromagnet for subsequently actuating the movement.

11. In an electric clock, a movement having an arbor and a ratchet fast thereon, a member journaled on the arbor carrying diametrically-disposed pawls engaging the ratchet, oppositely-disposed springs connected to said member at diametrically-opposite points, and an electromagnet having a core and diametrically-disposed oppositely-pivoted armatures connected at their free ends to said member for stressing said springs when attracted by the core. 70 75

12. In an electric clock, a movement having an arbor and a ratchet fast thereon, a substantially balanced member journaled on the arbor carrying diametrically-disposed pawls engaging the ratchet, oppositely-disposed springs connected to said member at diametrically-opposite points, and an electromagnet having a core and diametrically-disposed oppositely-pivoted armatures connected at their free ends to said member for stressing said springs when attracted by the core. 80 85

13. In an electric clock, a movement, and electromagnetically - operative actuating mechanism therefor including an energizing winding, a source of electric current, circuit connections between said source and said winding including electric contacts, a pivoted arm on which one of said contacts is mounted in coöperation with the other, and means responsive to said actuating mechanism for striking said pivoted arm while the contacts are closed to quickly separate them. 90 95

14. In an electric clock, a movement having an arbor with a ratchet mounted thereon, a member carrying a pawl for engagement with said ratchet, an electromagnet 105 having an energizing winding and an armature connected to said member, a source of electric current, circuit connections between said source and said winding including electric contacts, a pivoted arm carrying one of 110 said contacts in coöperation with the other and extending into the path of movement of said member, the construction and arrangement being such that, upon attraction of the armature resulting from the closure 115 of said contacts, said member is moved by the armature and strikes the pivoted arm to quickly separate the contacts.

15. In an electric clock, a movement having an escapement, electromagnetically-operative actuating mechanism therefor including an electromagnet and a spring adapted to be rewound intermittently, an interwinding mechanism including an arm engageable with the escapement and forming an armature of the electromagnet, whereby when the electromagnet is energized to rewind the spring, the interwind- 120 125

ing mechanism is engaged with the escapement to replace thereon the pressure of the actuating mechanism.

16. In an electric clock, a movement having an escapement, electromagnetically-operative actuating mechanism therefor including an electromagnet and a spring

adapted to be retensioned intermittently, an interwinding mechanism including a yieldable arm carried by an armature of the electromagnet for engagement with the escapement while the spring is being retensioned. 10

In testimony whereof I affix my signature.
LOUIS E. SHAW.
